UNITED STATES PATENT OFFICE

OSCAR TERVO, OF QUINCY, MASSACHUSETTS, ASSIGNOR TO UNITED MATTRESS MACHINERY COMPANY, OF BOSTON, MASSACHUSETTS, A CORPORATION OF MAINE

SIDE STITCHING A MATTRESS

Application filed February 21, 1930. Serial No. 430,173.

This invention relates to the side stitching of mattresses and has for its general object to provide a novel method of introducing side stitching into mattresses, according to which the stitches are formed successively and as each new stitch is formed sufficient thread is drawn from one stitch to the next through the line of stitching to supply the thread for the newly formed stitch. The drawing of the thread from one stitch to another is secured by applying a pulling strain on the thread simultaneously at a plurality of points along the line of stitching thereby obviating the strain which would be put on the thread if the entire force for pulling the thread forward to form each stitch were applied at the needle end of the thread.

In order to give an understanding of my invention I have illustrated herein one way of practicing it which will now be described, after which the novel features will be pointed out in the appended claims.

Fig. 1 of the drawings is a perspective view illustrating the manner in which the side stitch is inserted in the mattress.

Figs. 2, 3, 4, 5, 6 and 8 are sectional fragmentary views showing steps in the process of side stitching the mattress.

Fig. 7 is a fragmentary view illustrating the character of the side stitching.

Before describing the manner in which the stitches are formed I will refer to the character of the side stitching.

In the drawings 1 indicates the mattress and in Fig. 7 is illustrated the character of side stitching. The mattress comprises the usual ticking 2 and the filling material 3. The side stitching comprises a series of stitches 4, each entering the ticking at one point and passing around a quantity 25 of the filling and then emerging from the ticking at another point. The successive or adjacent stitches are connected by the short portions 5 of thread which lie on the outside 45 of the ticking. In the construction shown, the stitches are so arranged relative to each other that there is a slight overlapping of adjacent stitches, each end of each stitch overlapping somewhat the meeting end of an adjacent stitch. For instance, as shown in Fig.

7, the point 6 where the thread of each stitch 4 emerges from the ticking is situated slightly beyond the point 7 where the next stitch enters the ticking. For convenience I will refer to the points 7 where the thread of each stitch enters the ticking as the "point of entrance", and the point 6 where each stitch emerges from the ticking as the "point of emergence." The portions of thread between the point of emergence 6 of one stitch and the point of entrance 7 of the adjacent stitch constitute short connecting portions which lie on the outside of the ticking. With this manner of stitching there will be formed small closed loops 8 constituted by overlapping ends of two adjacent stitches and larger open loops constituting the stitches proper. All the stitches lie in the same plane and the points of entrance and points of emergence for a series of connected stitches are all in the same line.

This stitching is formed through the medium of a curved needle 10 which is manipulated so that it enters the ticking at a point of entrance 7 at one end of the stitch 4 and passes around through the filling 3 in a curved path and emerges from the ticking at a point of emergence 6 at the other end of the stitch, the thread 14 which is attached to the needle being drawn around through the filling in the same curved path thereby to produce the stitch 4. After the needle has made one pass it is shifted along the side edge of the mattress into a position to form the next stitch but the distance which it is thus shifted is slightly less than the length of the stitch previously formed so that when the needle enters the mattress for making the second stitch the second point 7 of entrance will be in the rear of the point 6 of emergence for the previous stitch. The second stitch is then formed in the manner above described, the curved needle passing through the filling 3 from the point of entry 7 to the point of emergence. In order to form this second stitch, however, it is necessary to draw the thread through the mattress from the entry point 7 to the emergence point 6, and to enable this operation to be performed my improved method contemplates acting on the

portion 5 of the thread between the point of emergence 6 of the first stitch and the point of entry 7 of the next stitch thereby to draw a sufficient length of thread through 5 the previous stitch to form the next stitch. This operation is repeated as the successive 10 stitches are made so that as the stitching proceeds the thread is acted upon at each point 5 to draw from the previous stitch enough 15 thread to form another stitch, this length of thread thus being passed from one stitch to another and on to the needle as the successive 20 stitches are formed.

The drawings show in a somewhat dia- 25 grammatic manner a device by which this operation of drawing the thread from one stitch to another may be carried out. As shown in Fig. 1, I propose to employ a device comprising a plurality of rotary pins 11 30 which are arranged so as to encircle the mattress 1 to be side stitched, said pins bearing against the side face 12 of the mattress. The pins are preferably so situated that they press into the side face of the mattress slightly 35 thereby causing the mattress to bulge out between the pins as shown at 13. These pins are suitably supported and are each capable of rotating. The pins will also be spaced apart a distance slightly less than the total 40 length of each stitch 4. The various steps involved in forming the stitches are best seen in Figs. 2 to 6 inclusive. Fig. 2 illustrates, for instance, the beginning of the first stitch. The needle 10 is placed so that it will enter 45 the ticking 2 at the point 7 which is closely adjacent one of the pins 11 and the needle is carried around through the mattress filling as above described and will emerge from the ticking at the point 6 which is on the opposite 50 side of the next adjacent pin 11a. The needle thus encircles two adjacent pins during its pass through the filling. Fig. 2 shows the needle just entering the mattress and Fig. 3 shows the point of the needle just emerging 55 from the mattress. It will be understood, of course, that the needle has the thread 14 attached thereto.

From the position shown in Fig. 3 the 60 needle is given another half turn into the dotted lines shown in Fig. 5, this operation drawing a length of thread around through the filling of the mattress to form the stitch 4. When the needle has thus made one pass it is shifted from the left hand dotted line position shown in Fig. 5 backwardly to the full line position and then is shifted longitudinally of the ticking in the right hand dotted line position shown in Fig. 5, this operation, of course, drawing the thread 14 through the 65 filling of the mattress. When the needle has been brought to the right hand dotted line position in Fig. 5 it is given another turn or pass which carries it into the ticking at the point 7a on the opposite side of the pin 11a 70 from which it emerged in forming the previ- 75

ous stitch, the needle being carried through the mattress as shown in Fig. 8 and emerging from the point 6a just beyond the pin 11b, the said needle in its second pass also encircling two pins. The formation of the second stitch tightens the thread about the pin 11a and as the needle is shifted into position to form the next stitch the turning movement of the pin 11a in the direction of the arrow serves to draw sufficient thread through the length of the first stitch to form another stitch.

As the next stitch is formed the thread is wrapped about the pin 11b and the rotation of the pins 11a and 11b serve to draw the thread from the source of supply through the stitches formed in sufficient quantity to supply the thread for the next stitch. This operation is repeated as each stitch is formed and until the stitching has been carried clear 80 around the mattress.

By the time the stitching is completed all of the pins are operating to draw thread from one stitch and deliver it to the next 90 stitch. Since the thread is thus delivered from one stitch to another it follows there is no accumulated strain on the thread at the needle end for the thread at the needle is at no time subjected to any greater strain than is necessary to draw the thread through the 95 mattress for the formation of a single stitch.

It will be understood, of course, that any suitable mechanism may be employed for manipulating the needle and merely as illustrating a device adapted for this purpose I have shown a swinging needle-gripping arm 16 which is mounted on a rock shaft 17 situated at the center of the curvature of the needle. The end 18 of this arm is arranged to grip the needle as the arm swings in the direction of the arrow in Fig. 2 thereby to turn the needle around as shown in Fig. 3, the needle being guided in such movement through a guide member 19. When the arm 16 has been swung into position shown in Fig. 3, the point of the needle has emerged from the ticking and the arm is then swung back into position shown in Fig. 4 to grip the point of the needle. The arm is then given another half rotation to bring the needle into the dotted line position Fig. 5 thereby to draw the thread through the mattress for formation of the stitch 4 and at this time the shaft 17 is moved away from the mattress to carry the needle into the full line position Fig. 5 thereby clearing the needle from the mattress and then it is shifted along to the right hand dotted line position which places the needle ready for the next pass through the mattress 120 and the above operations are repeated.

It will be understood that one or more lines of stitching may be inserted in the side edge of the mattress. Fig. 1 shows three lines of stitching being inserted but the method here- 125 130

in described is applicable to one or more lines of stitching.

After the stitching has been carried clear around the mattress the pins 11 are then withdrawn from the loops 8. I propose to withdraw these pins progressively beginning with the pin at the first stitch and as each pin is withdrawn the rotation of the succeeding pins will serve to tighten the stitch at which the pin is withdrawn. The stitches are thus tightened progressively around the mattress.

In carrying out this method all the stitches of any row of connected stitches are formed in the same plane and all the points of entrance and points of emergence for the different stitches of the said row are in line with each other.

I claim:

20 1. The method of side stitching a mattress which consists in forming a series of connected stitches in the side of the mattress, all of which occupy the same plane, by carrying the thread for each stitch into the ticking at 25 one point and around a portion of the filling and then out through the ticking at another point spaced from the entering point of the adjacent stitch, whereby there will be a short length of thread on the outside of the ticking for each stitch and applying an independent pulling force on each such short length with the application of the independent pulling forces on all the short lengths occurring simultaneously, whereby each 30 independent pulling force draws from one 35 dependent pulling force draws from one stitch for delivery to the next stitch a sufficient length of thread to form a new stitch.

2. The method of side stitching a mattress which consists in inserting the thread through 40 the ticking at the side face of a mattress at a point of entrance, passing the thread around a portion of the filling and out through the ticking at a point of emergence, again inserting the thread through the ticking at a second point of entrance situated in 45 line with the first two points but spaced from the point of emergence and passing the thread again around a portion of the filling and out through the ticking at a second point of 50 emergence also in line with the other points, repeating these operations to form a series of stitches around the side face of the mattress which are connected by short lengths of thread on the outside of the mattress, and 55 applying an independent pulling force on each such short length with the application of the independent pulling forces on all the short lengths occurring simultaneously whereby each independent pulling force 60 draws from one stitch for delivery to the next stitch a sufficient length of thread to form a new stitch.

In testimony whereof, I have signed my name to this specification.
